UNITED STATES PATENT OFFICE.

RAYMOND M. ROBERTS, OF MELROSE HIGHLANDS, MASSACHUSETTS.

PLATFORM FOR USE WITH ELEVATING-TRUCKS.

1,349,917.

Specification of Letters Patent. Patented Aug. 17, 1920.

Application filed September 24, 1919. Serial No. 326,092.

To all whom it may concern:

Be it known that I, RAYMOND M. ROBERTS, a citizen of the United States, residing at Melrose Highlands, county of Middlesex, 5 State of Massachusetts, have invented an Improvement in Platforms for Use with Elevating-Trucks, of which the following description, in connection with the accompanying drawing, is a specification, like 10 characters on the drawing representing like parts.

This invention relates to platforms such as are used in connection with so-called elevating trucks. These platforms are made 15 with a load-supporting portion and with suitable legs which support the load-supporting portion a proper distance from the floor to permit the elevating truck to be run under the platform, and then when the truck 20 is elevated it lifts the platform from the floor so that the platform can be transported on the truck.

The object of my invention is to provide 25 an improved platform which can be manufactured at a small cost, which meets all the requirements of a platform of this type, and which is constructed so that it can be shipped to the purchaser in a knocked-down state thereby saving transportation charges. 30 The platform is also constructed so that if desired the purchaser may buy simply the side sills or frame of the platform and may then complete the platform by nailing to the sills planks or boards to constitute the load-supporting portion of the platform. In this 35 way the purchaser secures a platform at a less cost partly because the sills or frame can be shipped at less expense than the complete platform and partly because he does not 40 have to pay the manufacturer a profit on the lumber which constitutes the load-receiving portion of the platform.

Further objects of the invention are to 45 provide a platform having other features of improvement, all as will be more fully hereinafter set forth.

In order to give an understanding of my 50 invention, I have illustrated in the drawings a selected embodiment thereof which will now be described, after which the novel features will be pointed out in the appended 55 claims.

In the drawings, Figure 1 is a perspective 60 view of a platform embodying my invention with portions broken out to show better the 65 construction;

Fig. 2 is a transverse sectional view through the sill taken adjacent one of the legs;

Fig. 3 is a perspective view of one of 60 the legs;

Fig. 4 is a view of the blank from which the leg is made.

My improved platform comprises two sill members extending longitudinally of the 65 platform, each having a metal section to give strength thereto and also comprising a nailing strip, a load-supporting portion which rests on the sills and is nailed to the nailing strip, and legs for supporting the 70 sills which are constructed so as to give proper support to the nailing strip as well as to the metal portion of the sill. The two sills are indicated generally at 1, and each comprises an angle-iron section 2 arranged 75 with one flange 3 extending horizontally and the other flange 4 extending vertically, and a nailing strip 5 which is secured to the angle-iron section 2.

Each nailing strip is made from wood or 80 other suitable material adapted to receive nails, and it is fitted into the corner of the angle-iron member 2, said nailing strip preferably having a thickness substantially equal to the vertical dimension of the angle-iron, but having a width greater than the angle-iron so that it projects beyond the horizontal flange 3. The two sills are arranged with their horizontal angles directed 85 outwardly and the nailing strips 5 are situated on the outside of each sill. Each nailing strip is fitted to the angle-iron so that the top surface of the nailing strip comes flush with the top of the flange 3. Each sill is provided with two or more legs on 90 which it is supported, said legs being indicated generally at 6. The construction of these legs will be presently described.

The load-supporting portion of the platform is in the form of a plurality of boards 100 or planks 7 which rest on the sills 1 and are nailed or otherwise secured to the nailing strips 5. The legs 6 are preferably made of sheet metal bent into the desired shape. Each leg is formed with the two sides 8 and 105 9 extending at right angles to each other and the side 8 is provided with the extension 10 which fits between the vertical leg of the angle-iron and the inside edge of the nailing strip, said extension being riveted 110 or secured to the angle-iron by suitable fastening means 11. The side 9 of the leg is

formed at its upper end with a horizontal flange 12 situated below the top of the extension 10 and in position to extend under and support the nailing strip 5. This flange 5 12 is bolted to the nailing strip by suitable bolts 13. The lower ends of the two sides 8 and 9 are connected by a foot portion 23. A leg of this sort can conveniently be made from a blank of sheet metal having 10 the shape shown in Fig. 4 by bending said metal along the dotted line 14 to form the two sides and then bending the upper edge of one side along the line 15 to form the flange 12. The portion 23 of the blank is 15 bent to form the foot of the leg. I will preferably weld the foot 23 to the side 8 at 17 and also weld the edge of the flange 12 to the side 8 at 18, thus adding strength to the leg. A leg having this construction can 20 be easily made and is extremely strong.

One advantage of my invention is that it provides a platform which can be assembled by the purchaser. All the purchaser needs to buy are the two sills with the connected 25 legs. Upon receiving these he can readily cut boards or planks 7 to the required length and nail or bolt them to the nailing strips, and when this is done, the platform is completed. This not only saves transportation 30 because of the small space in which the sills can be shipped compared with the space required for the completed platform, but also avoids the necessity of the purchaser paying a profit to the platform manufacturer on 35 the lumber used for the load-supporting portion thereof.

I claim:

1. In a platform for elevating trucks, the combination with two sills, each having a 40 nailing strip extending longitudinally thereof, of legs supporting said sills, and a wooden load-supporting portion resting on the sills and secured to the nailing strips.

2. In a platform for elevating trucks, the combination with two sills, each comprising 45 a metal strength-giving element and a nailing strip secured thereto, of legs supporting said sills, and a wooden load-supporting portion resting on the sills and secured to the nailing strip.

3. In a platform for elevating trucks, the combination with two sills, each comprising

an angle-iron member and a nailing strip secured thereto, of legs supporting said sill, and a wooden load-supporting portion resting on the sills and secured to the nailing strips. 55

4. In a platform for elevating trucks, the combination with two sills, each comprising an angle-iron strength-giving element and 60 a wooden nailing strip having its top edge flush with the top of the angle iron, of legs supporting said sills, and a wooden load-supporting portion resting on the sills and secured to the nailing strips. 65

5. In a platform for elevating trucks, the combination with two sills, each comprising a metal strength-giving element and a wooden nailing strip, of legs secured to the metal element of each sill and having a portion extending under and supporting the nailing strip, and a load-supporting portion resting on the sill and secured to the nailing strip. 70

6. In a platform for elevating trucks, the combination with two sill members, each having a metal strength-giving element and a wooden nailing strip, of sheet metal legs for supporting the sills, each presenting two sides arranged at right angles to each other, 75 one side extending longitudinally of the sill and secured at its upper end to the metal section thereof and the other side extending transversely to the sill and constituting a support for the nailing strip, and a load- 80 supporting portion sustained by said sills. 85

7. In a platform for elevating trucks, the combination with two sills, each having an angle-iron strength-giving element and a nailing strip secured thereto, of sheet metal 90 legs supporting the sills, each leg presenting two sides arranged at right angles to each other, one side having at its upper end an extension which is located between the angle-iron and the nailing strip and is secured to 95 the former and the other side having at its upper edge a horizontal flange which extends transversely of and supports the nailing strip, and a load-supporting platform sustained by the sills. 100

In testimony whereof I have signed my name to this specification.

RAYMOND M. ROBERTS.
